UNITED STATES PATENT OFFICE

2,591,726

CHEST OR CONTAINER STRUCTURE

Moritz Schoen, New York, N. Y.

Application March 8, 1947, Serial No. 733,405

6 Claims. (Cl. 312—201)

1

This invention relates to portable containers, boxes or chests which may be used for many purposes, such as for holding tools, yarn and other sewing utensils, confectionary articles etc. Such containers may, therefore, be made of wood, plywood, metal or any other suitable material, such as cardboard, plastic and plastic composition.

Containers or boxes of the portable type and of heretofore known structures have certain drawbacks in that the tray or box sections of which such container consists, are swingably or otherwise hinged or connected to each other, so that access to a predetermined center or bottom section can only be had by swinging either all sections of the structure to open condition or at least those sections which are located at that side of the container to which access is desired.

These known container structures employ a lever or brace system extending on the outer walls of the tray sections, so that the container becomes bulky and deficient in outer appearance.

The present invention overcomes these and other disadvantages and has as one of its objects the provision of means facilitating independent arrangement and movement of the tray or drawer sections of the container and also permitting their stepwise or stairwise disposition to each other, when the container is entirely open and affords substantially full access to any and all of said drawer sections.

It is another object of this invention to provide means affording a very compact and space saving holding and carrying device of the aforesaid character in which any suitable articles may be quickly accommodated and stored.

A further object of the present invention is to provide means offering the possibility of holding articles in a desired and orderly fashion, ensuring a rigid and inexpensive container structure, which may be manufactured by mass production methods and which in closed as well as in extended or open position is stable, fulfills all desirable requirements of the practice, and is aesthetic in appearance.

Yet, another object of the invention is the provision of means reducing the surfaces of frictional engagement of the tray or drawer sections of said container to a minimum, aiding in the guidance of said sections with respect to each other during sliding movement, and contributing to a simplified assembly of the sections or parts of which the container consists.

Still, a further object of the invention is to provide means enabling the reinforcement of the

2

corner parts of said drawer or tray sections and the formation of stops which limit and adjust the sliding movements of said sections.

A still further object of the invention is the provision of means rendering possible the longitudinal sliding movement of said drawer sections with a predetermined additional throw.

Other objects of the invention will be pointed out in the following description and claims and illustrated in the accompanying drawing which discloses, by way of example, the principle of the invention and a preferred mode which has been contemplated of applying said principle.

In the drawing:

15 Fig. 1 is a longitudinal sectional view of the container embodying the invention, the drawer sections of one side of said container being shown in open or extended position.

Fig. 2 is a top plan view of the container, as seen in Fig. 1.

Fig. 3 is a cross-sectional view of the container taken along line 3—3 of Fig. 1 as seen from the bottom of the container.

Fig. 4 is a vertical sectional view of the container taken along line 4—4 of Fig. 1.

Fig. 5 is a sectional view of the slide of the container, as seen in one position.

Fig. 6 is a sectional view of the slide of Fig. 5 in another position.

30 Referring now more particularly to the drawing, there is shown in Fig. 1 a cabinet in form of a chest or container 10 made in accordance with this invention. This container may be made from glass, wood, metal, plastic, plastic composition or any other suitable mass. In this instance, the container is supported on pairs of legs 11 and 12.

Container 10 has a base or lower compartment 13 forming a common support for the drawer halves or drawer side parts 14 and 15, which in closed position of said container are disposed on the open top of said compartment 13.

Container side part 14 includes holding elements, such as drawer or tray sections 16, 17, 45 section 16 being closed by a cover or lid 18 from which handle 19 projects; the container side part 15 consists of the holding elements in the form of drawer sections 20 and 21, of which section 21 is closeable by a slideable cover 22 provided with a handle 23.

On the right hand side of Fig. 1, drawers 20 and 21 as well as cover 22 are shown in their extended or open positions (full lines), whereas side part 14 is shown in its closed position.

It will be apparent from this carrier or hold-

ing structure 10 that side parts 14 and 15 with drawer sections 16, 17 and 20, 21 as well as respective covers 18 and 22 may be independently operated by sliding movements, for example, by employing handles 19 and 23, in order to obtain access to the interior of the respective drawer sections.

As seen in Fig. 1, the right hand portion of the lower compartment 13 has been made accessible by moving or sliding drawer section 20 in outward direction according to arrow A. It is well understood that the left hand portion of compartment 13 may also be made accessible by moving drawer section 17 in outward direction according to arrow B. This access to the lower compartment 13 may be had without moving upper sections 21, 16 and their respective covers 22 and 18 to extended position, as may be easily realized.

Figs. 1 and 4 show the lower compartment 13 in section, having a bottom wall 24 and end walls 25, 26 to which said bottom wall is joined in any known manner. The open compartment 13 has further the side walls 27 and 28 which are provided below their upper edge with longitudinal grooves 29 and 30 for a purpose later described.

Abutting against end wall 25 and side walls 27, 28 at their respective corners are pairs of stop members 31, 32 which project somewhat beyond the upper rectangular edge 33 of end walls 25, 26 and side walls 27, 28. These projecting ends of the stop members 31, 32 are designated by numerals 31a and 32a (Fig. 1).

The channel-shaped recesses or grooves 29 and 30 are adapted to receive therein the projecting flanges 34, 35 of slide members about to be described.

All the slide members may be of the same dimensions. A pair of spaced slide members is preferably affixed to one end of the bottom of each drawer section and also to one end of each cover. In the present instance, the pair of slide members or rails 36, 37 which are affixed to the bottom of cover 18 by means of nails or other fastening means 38, are shown to be of lesser height and greater length than the pairs of slide members 39, 40 of tray section 16 and slide members 41, 42 of the tray section 17.

As it is well apparent, the pair of slide or rail members 39, 40 is affixed to the underface of bottom 43 of section 16 by means of nails or other fastening means 44 and so is the pair of slide or rail members 41, 42 affixed to the underface of bottom 45 of section 17.

This same arrangement applies also to the right side part 15 of the container 10, as it has been just described with respect to the left side part 14 and its respective sections.

As may be realized from the open or extended right side part 15 of the container 10, tray section 20 is provided with a pair of stop members 46 similar to and arranged in like manner as the pairs of stop members 31 and 32, as seen in Figs. 1 and 3. A further pair of stop members 47 is arranged within drawer section 17 and both these pairs of stop members 46 and 47 project beyond the upper edge of the respective tray sections 20 and 17 to form projecting ends 46a and 47a, respectively.

All these pairs of stop members are adapted to reinforce the respective corner portions of the lower compartment 13 as well as those of the tray sections 17 and 20.

In order to more clearly explain the function and relative positioning of the tray sections and

covers with respect to each other, tray section 20 is hereinafter more fully described and it is well understood that such description applies also to the remaining tray sections.

Drawer or tray section 20 has the end walls 50, 51 and the side walls 52, 53 to which walls is joined the bottom wall 54. Within the corner portions formed by the end wall 51 at the side walls 52 and 53, respectively, is positioned the pair of stop members 46, as it is well apparent from Figs. 1 and 3. End walls 50 and 51 project somewhat below the bottom wall 54, as may be seen from Fig. 1 and so do the side walls 52 and 53 in a manner that the pair of slides 55 which is attached to the bottom 54 of tray section 20 by means of nails 56, will be accommodated within the respective recessed corner spaces and projects therefrom in downward direction beyond the projecting side and end walls 50, 51 and 52, 53. It is further to be observed that the pair of slide members 55 abuts against the end wall 55 and adjacent side walls 52, 53.

As can be further seen from Fig. 1, side wall 52 is provided at its upper end with a longitudinal groove 52a. In a similar way, side wall 53 is provided with a longitudinal groove so that a pair of slide members 60 fixed to the bottom 61 of tray section 21, which is of identical construction as pair of slide members 55 or 41 and 42 (Fig. 4), may move or slide along such longitudinal grooves provided in said side walls 52 and 53.

Let it be assumed that the container 10 is in closed condition and the right side part 15 assumes a position as indicated in dot-dash lines (Fig. 1). If it is now desired to obtain access to the right side of the lower compartment 13, all that is to be done is to slide tray section 20 as aforesaid in the direction of arrow A while the upper tray section 21 and cover 22 may remain in superposed position on each other and are carried by tray or drawer section 20. During movement in the direction of arrow A, section 20 is guided by means of the pair of slide members 55 along the guide grooves 29 and 30 until the pair of slide members 55 abuts against the projecting ends 32a of stop members or means 32 which latter are fixed on end wall 26. These projecting ends 32a during such sliding movement of section 20 engage with extremely slight friction the lower surface of bottom 54 and the inner edges 52b and 53b of the downwardly projecting side walls 52 and 53, respectively so that although relatively short slide members 55 are employed, tray section 20 will be securely guided with a minimum of frictional surface engagement.

If it is now desired to also open tray section 20, all that is to be done is to move tray section 21 in the direction of arrow C relatively to tray section 20, as it is apparent from Fig. 1, and if it is desired to open or get access to tray section 21, cover 22 is to be moved in the direction of arrow D.

The same principle hereinbefore described in greater detail with respect to tray section 20, and also mentioned with respect to compartment 13, tray section 21 and cover 22 of the right side part 15 of container 10 is applicable and employable with respect to the left side part 14 with its respective tray or drawer sections.

It is to be noted that no limiting stop members, as described with respect to compartment 13 and tray sections 17 and 20 are needed for tray sections 16 and 21 to prevent the respective covers 18 and 22 from moving outwardly beyond their respective tray sections to which they are applied

since the pair of slide members attached to the bottom surface of covers 18 and 22 will abut against the respective end walls of tray sections 16 and 21 in the outermost and extended positions of said covers.

It will further be observed that the pairs of stop members 31, 32 and 48, 47 hereinbefore described fulfills the further purpose of engaging in closed condition of the container 10 the downwardly projecting end walls of the respective tray sections while the slide members of the latter act as stop members and abut against the opposite end walls of the respective tray sections, thus contributing to a perfect alignment of the superposed tray sections with respect to each other when the container 10 is in closed condition. As a consequence, a slight space 62 will be obtained so that direct contact of the opposite tray sections will be avoided and their damage or wear will be eliminated.

As will be realized from Fig. 1, the length of each pair of slide members is so chosen that in open position of the respective tray sections at least two-thirds of the open top of each section will be made accessible.

Another advantage of selecting slide members of such reduced length is that when the tray sections are made from wood which can give or other springy material, the assembly of the container or its tray sections may be accomplished in a more simplified manner. For instance, by somewhat forcing the side walls 21 and 28 at their center portions in outward and transverse direction with respect to each other, engagement and disengagement of the pairs of slide members 41 and 55 with respect to grooves 29 and 30 may be easily effected and thus the assembly and removal of the upper section or sections 17 and 20 with respect to the lower compartment 13 may be readily and easily achieved.

As seen from Fig. 1, the container may be easily grasped by means of handles 19 and 23 and carried by the hand of a person from place to place.

The container 10 is shown in rectangular form, but it is well understood that the same may assume any other contour and designs while the same principle as hereinabove described is applied to said container.

In the embodiment shown, at least two-thirds of the respective open ends of the tray sections may be made accessible in extended or open position of container 10. In some instances, it might be preferred to increase the accessibility of these tray sections. To this end, reference is herewith made to modified, yieldable slide members, as exemplified in Figs. 5 and 6.

These figures are fragmentary sectional views of a corner portion of compartment 13, the section being taken at a level similar to that shown in Fig. 3. Against stop 32 abuts a slide 70 which, in this instance, consists of two spaced slide portions 71 and 72 which are interconnected by a rod member 73 carrying a coil spring 74. Rod 73 is fixedly anchored within slide member 72 at 75 and has an extension 76 which is guidedly positioned within slide portion 71 and terminates into a head piece 77 adapted to rest within a correspondingly shaped recess 78 within slide portion 71. Slide portion 71, as may be realized from Figs. 5 and 6, is fixed as by nails 79 to the bottom of the superimposed tray section (not shown), whereas the spaced slide portion 72 is securely held in its position and in sliding engagement with a suitable groove (not shown) by means of said rod 73.

As soon as the tray section carrying slide 70 abuts against stop member 32, the rod extension 76 will be pressed to project beyond slide portion 71 which will then be moved against the action of spring 74 toward slide portion 72, as seen in Fig. 6. Thus, an additional throw or stroke may be obtained to make the compartment or tray positioned underneath slide member 70 accessible to a larger extent. Upon release of the pressure exerted against the tray section in the direction of stop 32, as indicated by arrow E, the slide portions 72 and 71 will be retracted or led back to normal position by means of the action of spring 74, as indicated in Fig. 5.

Such modified slide arrangement may be very advantageous in connection with heavy tool chests and similar devices.

It goes without saying that the aforesaid elements in form of tray sections may be equipped with partitions (not shown) or inserts provided with recesses for holding and accommodating tools or other implements.

Instead of trays or drawers, as seen in the drawing, plate-like or similarly shaped elements may be employed, as long as sliding, guiding and limiting movements thereof correspond to the principles of this invention set forth hereinabove.

It becomes now apparent that there has been provided according to this invention a box structure, chest or like container comprising an elongated base compartment with an open top formed by rectangular-shaped walls, side walls and end walls, respectively, at least two drawer sections arranged in side by side relation to each other and adapted to slide along the side walls of said base compartment, each of said drawer sections having a bottom wall, two end walls and two parallel side walls, said end walls and said side walls of each drawer section projecting downwardly beyond said bottom wall, a pair of slide members fixed to the bottoms of said drawer sections so as to abut against one end of said end walls of each drawer section, stop means spacedly arranged from each other and affixed to opposite end walls of said base compartment therewithin, said stop means projecting beyond said rectangular-shaped walls for sliding engagement with the bottoms of said drawer sections, respectively, said stop means engaging opposite end walls of said drawer sections in closed condition of said base compartment, and groove means for engagement with said slide members disposed at the adjacent side walls of said base compartment, said slide members abutting against said stop means in extended position of said drawer sections, whereby access to said open top of said base compartment may be had.

As many possible embodiments may be conceived of the above invention, and as alterations or changes may be made in the embodiments above set forth, it is to be stated that all matters hereinbefore explained or shown in the accompanying drawing, are to be interpreted as illustrative and not in a limitative sense.

Having thus described the invention, what is claimed as new and desired to be secured by Letters Patent, is:

1. In a drawer structure having a bottom and two parallel side walls projecting downwardly beyond said bottom, and a support for said drawer structure therebelow; the combination of a pair of slide members fixed to the underside of said bottom and at one end of said downwardly projecting side walls, with guide means spaced-

ly arranged from each other on said support, said guide means extending to said bottom and slidably engaging said bottom and said downwardly projecting side walls during sliding movement of said drawer structure, and groove means disposed for engagement with said slide members and carried by said support.

2. A drawer structure comprising a bottom, two end walls and two parallel side walls, said walls projecting downwardly beyond said bottom, a support for said drawer structure positioned therebelow, a pair of slide members fixed to the underface of said bottom and at one end wall, said slide members being spaced from each other and disposed at one end of said downwardly projecting side walls, and upwardly directed guide means spacedly arranged from each other on said support and projecting therebeyond for position adjacent the opposite end wall of said drawer structure, said guide means extending for contact with and slidably engaging said bottom and said downwardly projecting side walls during sliding movement of said drawer structure, said support being provided with parallel grooves disposed for engagement with said slide members, whereby said drawer structure is slidably guided with respect to said support, said guide means forming stops for abutment of said opposite end wall in one position and of said slide members in another position of said drawer structure relatively to said support.

3. A box structure, chest or like container comprising an elongated base compartment with an open top formed by rectangular-shaped walls, side walls and end walls, respectively, at least two drawer sections arranged in side by side relation to each other and adapted to slide along the side walls of said base compartment, each of said drawer sections having a bottom wall, two end walls and two parallel side walls, said end walls and said side walls of each drawer section projecting downwardly beyond said bottom wall, a pair of slide members fixed to the bottoms of said drawer sections so as to abut against one end of said downwardly projecting side walls and one end of said end walls of each drawer section, stop means spacedly arranged from each other and affixed to opposite end walls of said base compartment therewithin, said stop means projecting beyond said rectangular-shaped walls for sliding engagement with the bottoms of said drawer sections, respectively, said stop means engaging opposite end walls of said drawer sections in closed condition of said base compartment, and groove means for engagement with said slide members disposed at the adjacent side walls of said base compartment, said slide members abutting against said stop means in extended position of said drawer sections, whereby access to said open top of said base compartment may be had.

4. A box structure, chest or like container having an elongated base compartment with a rectangular top edge, a plurality of pairs of drawer sections arranged on said top edge of said base compartment in closed condition of the latter, each pair of drawer sections being arranged in side by side relation to each other, each drawer section having a bottom and two parallel side walls projecting downwardly beyond said bottom, a pair of slide members fixed to each drawer section, said slide members being disposed at the underface of said bottom and at one end of said downwardly projecting side walls of each drawer section, said slide members being positioned ad-

jacent each other, respectively, on each pair of drawer sections when said base compartment is in said closed condition, and stop means for said slide members, said stop means being spacedly arranged from each other and affixed to said base compartment and projecting beyond said top edge to extend for position at said side walls and adjacent the bottom of the pair of drawer sections above said base compartment, said top edge of said base compartment being provided with grooves disposed for engagement with said slide members.

5. A drawer structure comprising a bottom, two end walls and two parallel side walls, said walls projecting downwardly beyond said bottom, a support for said drawer structure positioned therebelow, a pair of slide members fixed to the underface of said bottom and at one end wall, each of said slide members being provided with a movable portion and with a fixed portion, said portions of said slide members being movable relatively to each other and being disposed at one end of said downwardly projecting side walls, and stop means arranged on said support and projecting therebeyond for position against one end wall of said drawer structure, said stop means guidingly engaging said bottom at said downwardly projecting side walls during sliding movement of said drawer structure, said support being provided with parallel grooves disposed for engagement with said slide members, whereby said drawer structure may be slidably moved with respect to said support, said stop means being adapted for engagement with said one end wall in one position and with said slide members in another position of said drawer structure, said slide member portions being relatively movable with respect to said stop means whereby said drawer structure may be additionally slid relatively to said support.

40 6. A structure of the character described comprising an elongated support, at least one element adapted to slide on said support, said element having a bottom wall, means projecting downwardly beyond said bottom wall and spacing the latter from said support, slide members fixed to said bottom of said element, and stop means positioned in the path of said slide members and affixed to said support to project therebeyond, said stop means slidably engaging said bottom of said element and extending into the space formed by said downwardly projecting means, said support being provided with groove means disposed for engagement with said slide members, said slide members abutting against said stop means in one position of said element, whereby access to said support may be had.
